CLAIM

The ornamental design for a display screen with graphical user interface as shown and described.

DESCRIPTION

FIG. 1 is a front view of a display screen with graphical user interface showing our new design; and, FIG. 2 is an enlarged view of the encircled portion labeled as 2 in FIG. 1.

The perimeters of the underlying portion of a display screen and the graphical user interface are understood to be flush. The even-length broken lines showing the remainder of the graphical user interface illustrates portions of the graphical user interface and forms no part of the claimed design. The short-long broken lines showing of the encircled portions in FIGS. 1-2 form no part of the claimed design. The short-short-long broken lines in FIG. 1 represent boundaries of the claimed design. The dotted broken line box in FIG. 1 forms no part of the claimed design. The difference in shading in FIGS. 1-2 indicates a contrast of appearance. The broken line text forms no part of the claimed design.
